UNITED STATES PATENT OFFICE.

JULES HALTENBERGER, OF JACKSON, MICHIGAN.

OILER.

1,257,223.

Specification of Letters Patent. Patented Feb. 19, 1918.

Application filed April 7, 1917. Serial No. 160,398.

To all whom it may concern:

Be it known that I, JULES HALTENBERGER, a citizen of Hungary, residing at Jackson, in the county of Jackson and State of Michigan, have invented a new and useful Oiler, of which the following is a specification.

It is the object of my invention to provide a better splash circulation of oil in the crank cases of internal combustion engines, and especially to produce a movement of the oil longitudinally of the crank case by the splash action.

In certain types of internal combustion engines, the oil is picked up from one end of the casing and carried therefrom automatically to the other end of the casing, and allowed to find its way back as best it can from the latter end of the casing to the former end. As a result, the cylinders toward one end of the casing—the one to which the oil is automatically carried—have an excess of oil, resulting in carbonization and consequent loss of power, while the cylinders toward the other end of the casing are insufficiently supplied with oil, resulting in lack of lubrication with its consequent loss of power.

In attaining the object of my invention, I provide splashes on the lower ends of the connecting rods which connect the cranks of the crank shaft to the pistons, which splashes dip into the oil in the bottom of the crank case as the crank shaft is rotated and are skewed so as to throw the oil lengthwise of the crank shaft; in combination with means for automatically feeding the oil from that end of the crank case toward which such splashes throw the oil to the other end of the crank case.

The accompanying drawing illustrates my invention.

Figure 1 is a side elevation of an engine equipped with my invention, with the crank case partly in section to show the crank shaft, connecting rods, and oil splashes; Fig. 2 is an elevation on a larger scale of the lower end of a connecting rod equipped with my oil splash; Fig. 3 is also an elevation of the lower end of such connecting rod, but taken from a view point at right angles from that from which Fig. 2 is taken; Fig. 4 is a bottom view of such connecting rod; and Fig. 5 is a plan of a blank from which the oil splash is made.

The engine 10 is shown with four cylinders 11, 12, 13, and 14, in which are pistons

which are connected by connecting rods 15 to the four cranks on the usual crank shaft 16, the crank shaft and connecting rods being located within the usual crank case 17 which has oil pockets 18 in the plane of each of the connecting rods for the pistons in the cylinders 11, 12, and 13, though ordinarily no such oil pocket is provided in the plane of the connecting rod for the piston 14 in the cylinder 14. At the rear end (the left in Fig. 1) the crank case 17 is provided with an enlargement 19 in which may be the usual transmission mechanism. The bottom of this enlargement 19 furnishes the main oil reservoir 20, from which oil is lifted in any suitable or usual manner into a pipe 21 which is turned up and enlarged at its rear end to receive the oil and slopes downward toward the front so as to convey the oil so received to and discharge it into the front end of the casing 17. All this is standard construction.

Attached to the lower end of each connecting rod 15 for the pistons in the cylinders 11, 12 and 13 is my skewed splash 25. This splash is made from a blank 26 of the form shown in Fig. 5, having two holes 27 for the reception of the bolts 28 which hold together the two halves of the head of the connecting rod 15, and this blank is doubled on itself along the line 29 and then bent at right angles in the opposite direction along the line 30, thus providing a base portion 31 which is clamped between main and supplemental nuts 32 and 33 on the bolts 28 and a splash portion 34 which extends at right angles to the base portion 31 and is at an oblique angle to the plane of movement of the connecting rod 15, as clear from Figs. 2, 3, and 4.

When the engine is in operation, oil is fed to the front (or right hand) end of the crank case 17 through the pipe 21, and gathers in the oil pocket 18 under the cylinder 11. The skewed splash portion 34 of the splash 25 on the connecting rod for the piston in the cylinder 11 dips into this oil pocket 18 and splashes the oil both through the crank case and lengthwise thereof toward the next pocket 18, under the cylinder 12. The splash on the connecting rod for the piston in this cylinder 12 splashes the oil from the second pocket 18 through the crank case and toward the third pocket 18, under the cylinder 13; and the splash on the connecting rod for the piston in the

cylinder 13 splashes the oil from the third pocket 18 through the crank case and toward the main oil reservoir 20. This provides a uniform lubrication for the various 5 engine cylinders; and prevents either excessive lubrication in the front cylinder 11 or a lack of lubrication in the cylinders toward the rear.

In order to prevent the nuts 32 and 33 10 from becoming loose, one or more corners of the base portion 31 of the oil splasher 22 may be bent up as shown on the lines 35, to provide lock nut tabs 33 for the nuts 33.

I claim as my invention:

15 1. In combination, a multiple cylinder engine having cylinders, pistons, a crank shaft, connecting rods connecting the crank shafts and pistons, and a crank case, said crank case having oil pockets in its bottom in the 20 planes of connecting rods, and skewed splasher on the ends of the connecting rods for dipping into said pockets and splashing oil therefrom longitudinally of the crank case.

25 2. In combination, a multiple cylinder engine having cylinders, pistons, a crank shaft, connecting rods connecting the crank shafts and pistons, and a crank case, and skewed splasher on the ends of the connecting rods for splashing oil longitudinally of the crank case.

35 3. In combination, a crank shaft, a crank case in which said crank shaft operates, connecting rods attached to said crank shaft, and skewed splasher on the end of said connecting rods for dipping into oil in the bottom of the crank case and splashing it longitudinally thereof.

40 4. In combination, a crank shaft, a crank case in which said crank shaft is mounted, and a skewed splashers rotatable with a crank of said crank shaft for dipping into oil in the bottom of the crank case and splashing it longitudinally thereof.

45 5. In combination, a crank shaft, a crank case in which such crank shaft is mounted, a connecting rod mounted on a crank of said crank shaft, and a skewed splashers fixed on

the end of said connecting rod for dipping into oil in the bottom of the crank case and 50 splashing it lengthwise of the crank case.

6. As an article of manufacture, an oil 55 splasher comprising a base member arranged for attachment to a connecting rod, and a skewed splashers portion in a plane transverse to that of the base portion.

7. As an article of manufacture, a sheet metal oil splashers, comprising a base portion provided with two bolt holes at the ends, a triangular portion doubled back on 60 the first portion, and a splashers portion bent transversely to said doubled-back portion and oblique to the line of the bolt holes.

8. As an article of manufacture, a sheet metal oil splashers, comprising a base portion provided with two bolt holes at the ends, and a splashers portion bent from the base portion in a plane transverse to that of the base portion and oblique to the line 65 of the bolt holes.

70 9. In combination, a multiple cylinder engine having cylinders, pistons, a crank shaft, connecting rods connecting the crank shafts and pistons, and a crank case, said crank case having oil pockets in its bottom in the 75 planes of connecting rods, skewed splasher on the ends of the connecting rods for dipping into said pockets and splashing oil therefrom longitudinally of the crank case toward one end thereof, and means for automatically feeding said oil toward the other end of the crank case.

10. In combination, a multiple cylinder engine having cylinders, pistons, a crank shaft, connecting rods connecting the crank 85 shafts and pistons, and a crank case, and skewed splasher on the ends of the connecting rods for splashing oil longitudinally of the crank case toward one end thereof, and means for automatically feeding said oil toward the other end of the crank case.

In witness whereof, I have hereunto set my hand at Jackson, Michigan, this third day of April, A. D. one thousand nine hundred and seventeen.

JULES HALTENBERGER.
